UNITED STATES PATENT OFFICE

2,350,617

BLACK-OUT DEVICE

Jerome E. Johnson, New York, N. Y., assignor to
 Tension Envelope Corporation, New York, N. Y.,
 a corporation of New York

Application April 7, 1943, Serial No. 482,201

12 Claims. (Cl. 160—90)

This invention relates to black out devices particularly for covering panes of windows and the like to prevent escape of light rays from an interiorly illuminated building, and has for its object to provide a simple and inexpensive device which is extremely effective when a black out is necessary and which may be readily adjusted to admit daylight into the building when desired.

Other objects are to provide a pane covering device capable of construction from a material available during time of war such as paper, fiber sheets or the like; to provide black out devices wherein slide members thereof may be left in position during daylight hours to serve as a sign; and to provide a black out device that serves to support the glass in case of breakage.

In accomplishing these and other objects of the invention, I have provided improved structure, the preferred form of which is illustrated in the accompanying drawings, wherein:

Fig. 1 is a perspective view of the inner face side of a black out device constructed in accordance with the present invention.

Fig. 2 is a similar perspective view of the outer face side of the device.

Fig. 3 is a view of the parts of the black out device illustrated in spaced relation, the slide supporting member being shown partly folded.

Fig. 4 is a perspective view of a portion of a window showing one pane on which the opaque sealing material is applied, ready to receive a black out device; another pane covered by a black out device with the closure slide in place; another pane with the envelope-like slide support in position with the closure slide removed; and another pane with the closure slide being inserted into the envelope-like support thereon.

Fig. 5 is a fragmentary perspective sectional view through a portion of the window and an applied black out device, the section being taken on the line 5—5, Fig. 4.

Referring more in detail to the drawings:

A designates a window comprising a frame B set within the wall of a building and having mullions C dividing the frame into a plurality of light admitting openings covered by transparent or translucent panes D as in conventional window construction of factories and other buildings. In times of war most factories are operating throughout the night and require considerable illumination to carry on the work in which they may be engaged, and therefore some means is required to prevent escape of light rays from the interior of the building. I am aware that various forms of black out devices are in use for such

purpose but they are high in price, difficult to install, and do not make a complete black out.

In carrying out the present invention, I provide a simple and inexpensive black out device formed of opaque fiberboard, paper, or paper-like material suitably colored to absorb light and having sufficient body to retain its shape. The device 1 includes an envelope-like supporting structure 2, folded from a blank 3 having shape to provide front and back portions 4 and 5, sealing flaps 6 and 7, and a closure flap 8. The flaps 6, 7 and 8 are preferably formed on the front portion 4 with the flap 8 located on the side opposite a line of fold between the front and back portions so that when the back portion is folded to overlie the inner face of the front portion, the sealing flaps 6 and 7 may be folded over and sealed to the outer face of the back portion to form a pocket 9 having an insert opening 10 co-extensive with the closure flap 8. The front and back portions are of a shape and size so that the folds 11, 12, 13 and 14, which constitute the edges of the envelope-like structure fit closely against the side faces of the mullions C or portions of the window frame when the device is applied over the inner face of a pane D, as later described.

In order to admit light, when desired, the front and back portions have openings 15 and 16 therein of a size to leave a considerable marginal frame 17 but which are capable of passing the necessary amount of light during daylight hours. Insertable into the pocket-like frame is a slide 18 of a size and shape closely following the member 2 so that the side and end edges 19—20 and 21—22 closely engage within the folds 11—12 and 13—14 to cover the openings 15 and 16 when a black out is necessary, there being sufficient overlap by the margins of the frame to trap any light rays that might tend to leak around the edges of the slide. The slide is preferably formed of the same material as the member 2 so that it does not reflect light rays. The corners thereof are also preferably rounded to facilitate insertion of the slide.

In order to retain the slide, the closure flap is preferably provided with a string or flexible tie 23 that has one end attached thereto by a button 24 and is adapted to extend across the inner opening so that the opposite end may be wrapped about a similar button 25.

In applying the black out devices, the inner face of the marginal portions of the panes D are painted with a non-reflecting opaque adhesive 26, which preferably extends around the edge faces of the mullions as indicated at 27. The devices

are then pressed against the window panes so that the outer marginal edges seal firmly thereagainst. When thus applied and with the slides in place, the panes are completely covered so that light rays from the interior of the building cannot pass therethrough. During daylight all of the slides, or a sufficient number thereof, may be removed to pass the desired amount of daylight into the building. This is readily effected by unwinding the strings 23 from the buttons 25 and raising the closure flaps 8 to expose the slide insert openings 10. The slides may then be readily withdrawn and placed aside. When a black out is required, the slides 18 are readily inserted by sliding them through the insert openings 10, with the closure flaps 8 serving as guides for facilitating entrance of the edges into the insert opening. The slide is pushed into position within the envelope-like frame and the closure flap 8 is folded against the adjacent marginal edge of the back portion 5. The string is then passed across to the opposite side and the free end is wound once around the button 25.

In cases where it is not necessary to remove all the closures or slides 18 in admitting daylight, those that are left in position may have the exterior sides printed with letters as indicated at 28 so that they may be used as signs during daylight hours.

While I have particularly illustrated a string tie for the closure flap, it is obvious that other types of fasteners might be substituted therefor without departing from the spirit of the invention. It is also possible to omit the fastener and tuck the flap into the insert opening if desired.

From the foregoing it is obvious that I have provided a very efficient black out device which is inexpensive to produce and may be constructed in large quantities on present envelope manufacturing machines. It is also obvious the devices are easily applied to the panes of a window and are readily manipulated to admit exterior light or to effect a black out.

What I claim and desire to secure by Letters Patent is:

1. A black out device including, a supporting member adapted to be attached in covering relation to a window pane and having an opening therethrough for passing light, and a closure for and in said opening and removable from covering relation with said opening of the supporting member.

2. A black out device including, a slide supporting member adapted to be attached in covering relation to a window pane and having an opening therethrough for passing light, a slide mounted in said supporting member to close said opening and removable from said opening, and means for positively retaining the slide in closing position.

3. A black out device for window and like openings including, an envelope-like supporting frame having an insert opening at a side edge thereof and having light passing openings in the respective sides thereof adapted to be registered with a window opening, and a closure for said openings insertable into the envelope-like supporting frame through said insert opening for covering the window opening.

4. A black out device including, an envelope-like supporting frame having front and back portions provided with registering light passing openings in said portions, and a closure movable within the envelope-like supporting frame to cover said light passing openings.

5. A black out device including an envelope-like supporting frame having front and back portions and provided with an insert opening at a side edge thereof said front and back portions having registering light passing openings therein, a slide in the envelope-like supporting frame and movable through the insert opening to uncover said light passing openings, and a closure flap for said insert opening to retain said slide in opening closing position.

6. A black out device including, an envelope-like supporting frame having front and back portions and provided with an insert opening at a side edge thereof, said front and back portions having registering light passing openings therein, a slide insertable into the envelope-like supporting frame through said insert opening, a closure flap for said insert opening to retain said slide, and means for retaining the closure flap in closed position.

7. A black out device including, an envelope-like supporting frame having front and back portions and provided with an insert opening at a side edge thereof said front and back portions having registering light passing openings therein, a closure insertable into the envelope-like supporting frame through said insert opening, a flap for said insert opening to retain said closure, a button on said flap and said supporting frame respectively, and a flexible tie fixed to one of said buttons and having removable connection with the other.

8. In combination with a frame and a transparent pane carried by said frame, an adhesive 35 of opaque properties applied to margins of the pane, a black out device including a member covering the pane and having sealing contact with the adhesive, said member having an opening therethrough for passing light, and a removable closure member for said opening.

9. A black out device including, an envelope-like supporting frame having front and back portions provided with an insert opening at a side edge thereof, said front and back portions having registering light passing openings therein, a slide movable in the envelope-like supporting frame through the insert opening to cover said light passing openings, a closure flap for said insert opening to retain said slide, buttons on said closure flap and said supporting frame, and a flexible tie fixed to one of said buttons and having removable connection with the other.

10. In combination with a frame and a transparent pane carried by said frame, an opaque adhesive applied to margins of the pane, a black out device including an envelope-like structure covering the pane and having sealing contact with the adhesive, said device having openings for passing light, and a slide insertable into said envelope-like structure to close said openings.

11. In combination with a window having a transparent window pane, an envelope-like structure covering the pane and having openings for passing light, a slide removably supported in said envelope-like structure, and means securing said envelope-like structure over the pane.

12. In combination with a window frame mounting, a transparent pane, an envelope-like structure having openings for passing light rays, a slide removably supported in said envelope-like structure to close said openings, and means for attaching the envelope-like structure to said pane and closing any space that may occur around the envelope-like structure.

JEROME E. JOHNSON.
